UNITED STATES PATENT OFFICE.

JAMES JOHNSON, OF ANTWERP, NEW YORK.

CLOTHES-LINE ATTACHMENT.

SPECIFICATION forming part of Letters Patent No. 695,397, dated March 11, 1902.

Application filed November 16, 1901. Serial No. 82,532. (No model.)

To all whom it may concern:

Be it known that I, JAMES JOHNSON, a citizen of the United States, residing at Antwerp, in the county of Jefferson and State of New York, have invented a new and useful 5 Clothes-Line Attachment, of which the following is a specification.

My invention relates to an improvement in clothes-line attachments, and particularly to 10 what is known as the "pulley" clothes-line—that is, an endless line suspended upon pulleys; and the object of my improvement is to provide a device capable of ready attachment to the line to prevent sagging thereof and also 15 to prevent the lines from separating after the clothes are hung thereon. My invention also provides an arrangement whereby the weight will equally rest upon both lines; and with these and other objects in view my invention 20 consists in the peculiar construction and novel combination of parts, as will be more fully referred to in the following specification, reference being had to the drawings, in which—

25 Figure 1 represents my invention as applied to clothes-lines. Fig. 2 is a perspective view of one side of the device detached. Fig. 3 is a similar view of the opposite side. Fig. 4 is a detail section taken about on the line 4 4 of Fig. 2. Fig. 5 is an inverted plan view. Fig. 6 is a detail section about on the line 6 6 of Fig. 2. Fig. 7 is a section on the line 7 7 of Fig. 4.

In the drawings I have illustrated my invention as applied to a clothes-line that is suspended between two posts; but it will of course be understood that the device is also applicable to lines suspended from windows to posts, which are more often found in lines 40 of the character known as "pulley" clothes-lines.

In carrying out my invention I employ a horizontal portion A, that is provided at its center with a vertically-extending post B, that 45 is provided with a slot B', which may extend to any suitable distance lengthwise of the post that may be found most practicable, one side of the post being cut away to form an entrance to the slot, as shown at B². The 50 horizontal member is provided upon opposite sides thereof with obliquely-arranged recesses

C, whose lower ends merge into grooves C', that extend to the ends of the said member. The upper ends of the recesses also merge into a groove C², that extends along the central portion of the member A and unites the said recesses, as shown. In practice the line is inserted in one of the recesses C, with one end resting in groove C' and the opposite end extending lengthwise in the groove C², and is 60 then inserted in the other slot C of the opposite end of the horizontal member and is held in the opposite groove C'. The line is then passed around the pulleys that are secured to the posts, with its upper strand resting in 65 the slot B' of the vertical post B. By this arrangement it will be readily seen that I provide a device for holding the two strands of the line together, and by the arrangement shown and described the manipulation of the 70 line will not in the least be interfered with.

It will of course be understood that when the line is of unusual length any number of the devices may be employed with equal effectiveness, and it will also be understood 75 that the device may be readily attached to the line without removing the same from the pulleys and also even after the clothes may have been placed upon the line.

In order that the device may be positively 80 held in position upon the line, I provide a turn-button D, that is held to the horizontal member A by means of a screw or nail D'. This device is intended to extend up along 85 side the post B to close the entrance to the slot.

From the foregoing the advantages of my improvement will readily appear to those skilled in the art to which it appertains.

Having thus fully described my invention, 90 what I claim as new, and desire to secure by Letters Patent, is—

1. A device of the kind described comprising a horizontal member having obliquely-arranged recesses formed therein, the lower 95 ends of which terminate in grooves extending to the ends thereof, and the upper ends being connected by a groove formed in the upper face of the horizontal member and a post projecting from the horizontal member 100, and having a slot arranged therein, one side of the said post being cut away to provide an

entrance to the slot and means for closing the said entrance substantially as shown and described.

2. A device of the kind described comprising the horizontal member having recesses arranged in the ends and upon opposite sides thereof, a slotted post projecting from the said horizontal member and having an entrance formed therein to the slot, and means for closing the said entrance, substantially as shown and described.

3. A device of the kind described, comprising a horizontal member having obliquely-

arranged recesses produced in the ends thereof, that extend from the top to the bottom of the said member, and a slotted post projecting from the said horizontal member, one side of the said post being cut away to form an entrance to the said slot, and a turn-button for closing the slot, substantially as shown and described.

JAMES JOHNSON.
